CLOTHING FOR CARDS AND THE LIKE

Application filed August 4, 1930. Serial No. 472,987.

This invention relates to clothing for cards for various uses and while for the purposes of the present disclosure the type of clothing will be discussed which is particularly applicable to textile fabrics, it will be understood that such cards may be used for many purposes.

In the usual clothing, the foundation employed is generally a fabric such as canvas through which the wire points are stapled and which is wound or tacked on the cylinders or clamped on the flats.

While this type of clothing has been in long and general use and is more or less standard in type, a great many difficulties have been experienced which have not been overcome in spite of constant efforts so to do.

One of these difficulties has been that the foundation having the characteristics of fabric had to be tempered and wound and stretched and re-wound for even an original installation. After use further re-windings were usually necessary.

Another difficulty which has been common has been that of the working of the wire points in the fabric at their base so that gradually slots or elongations of the aperture in the fabric occurred so that the teeth were not properly supported at their base and yielded too much to give efficient carding. Furthermore, due to the local stretching of the foundation loose places occurred known as blisters. At such spots the points sometimes rise with the foundation causing them to strike the flats or doffer. These blisters also provided areas in which the heads of the staples in the under-surface of the foundation were unsupported and the staples worked loose and the points were withdrawn giving too much clearance of the working surface and frequently when the clothing was removed for re-winding the staples in such areas would fall out and have to be replaced by hand.

The fabric foundation furthermore has had to be made in strips of considerable width in order to get sufficient strength. This increased the spiral of the wind placing the teeth at a disadvantageous position and causing the fibre to feed laterally to the

side of the roll. Furthermore, there has been considerable practical difficulty in getting the foundation strips trimmed so as to give close joints in winding, the tendency being either to trim too close to the teeth which are set in closely adjacent rows and thus not leave sufficient support for the wire or to cut too coarsely leaving too much of a spacing between the marginal teeth at the edge of contacting turns.

Other materials and fabrics have been attempted, such as leather and like materials, but they have all developed more or less of the troubles above enumerated. Special clothing has also been attempted, such as bent wire constituting both teeth and backing, this being wound edgewise on the drums or cylinders, but this necessitated a very difficult winding job and had other disadvantages.

The present invention contemplates a new type of clothing which overcomes these difficulties and possesses certain novel characteristics of very marked advantage.

Briefly, its concept is that of clothing in which the wire is set in metal foundation having perforations of such character as not only to receive the wire but to support it. Furthermore, the concept includes that of a clothing in which the heads of the wire staples may be soldered in place so that each nog or each row of nogs is firmly held in place and rust-proofed at the same time. This is preferably effected by tin dipping the entire strip so that the entire product is rust-proofed and all crevices filled and smoothed up. Such clothing, as will be later set forth in the more detailed description of the specification has many advantages as will be apparent to those skilled in the art. Notably such clothing being of very considerable strength is provided in relatively narrow strips which makes it possible to put on windings of very gradual spiral and with regular spacing of the teeth due to the clean cut edge. Increased strength also makes it possible to use fastenings only at the ends of the strips instead of requiring the frequent fastening as in the case of the old clothing. The old practice of tacking the foundation at frequent intervals of relatively few inches was not only incon-

venient, but usually resulted in the damaging of the wire.

As illustrative of the invention there is shown in the accompanying drawing a type 5 of clothing particularly adapted for the carding of cotton, although it will be understood that clothing of the type used for wool or for the stripping of tobacco or other materials may be prepared in the usual styles 10 and types desired by different manufacturers for different purposes.

In the drawing:

Fig. 1 is an enlarged section through a fragment of a strip of clothing in accordance 15 with the invention.

Fig. 2 is a back view of a portion of a strip.

Fig. 3 is a view showing the winding and fastening of such.

Fig. 4 is a view of a single tooth of straight type.

Fig. 5 is a similar view of a single tooth of beaded type.

Fig. 6 is a detail view of the means of fastening the clothing on the drum.

Referring to the drawing, there is indicated at 1 a clothing strip of metal such as soft steel or brass or any other suitable metal or alloy. The strip should be of such 30 material and such thickness as to be sufficiently flexible for winding on a drum or roll and should also be sufficiently ductile to permit the formation of bosses 2 formed by the punching of the holes 3. These holes are 35 punched from what is to be the rear side of the strip and are adapted to receive the wire teeth.

The teeth may be in the form of staples 4 as in Fig. 1, or of single points such as 5 or 6 40 as shown in Figs. 4 and 5. The holes may be punched in any well-known arrangement, usually in the form of the conventional nog, as indicated in Fig. 2.

In Fig. 2, the heads 4¹ of the teeth 4 are 45 soldered, by tin dipping the entire strip, filling the indentations of the holes 3 and the edges of the heads 4¹ so that the heads are not only firmly attached to the metallic foundation strip 1, but the whole protected against 50 rust. Our clothing is therefore unaffected by oil or water which frequently damaged the old card clothing.

In the form shown, Fig. 4, the single tooth 5 has a straight shank and is soldered in 55 place. As shown in Fig. 5, the tooth 6 is headed at 6¹ and may or may not be soldered as desired.

In Fig. 3, the clothing strip 1 is indicated as wound on a drum D, it being fastened 60 thereto at each end. One end fastening is indicated at 7. This fastening as indicated in Fig. 6 is a screw having a conical head, the clothing strip 1 being punched with a down-turned boss 1¹ which enters a conic counter-sunk seat d in the drum D. Our metal cloth-

ing may also be made by electrically welding wire pins or staples to the foundation strip.

As the metal clothing seat is not subject to stretching or shrinking, it is capable of being tightly wound on the drum D or clamped in a flat. On the drum or cylinder it is usually only necessary to fasten the strip at the ends, thus doing away with the frequent tackings such as have been heretofore necessary. In this way the clothing can be put in position without danger of disturbing the spacing of the teeth or of bending or deforming them. As the clothing is prepared, in carefully gauged strips with even edges, it is possible to put on the winding so as to have the adjacent teeth of contacting edges exactly spaced so that when a roll is clothed its entire surface is completely and uniformly covered.

Due to the rigid mounting of the teeth in such a clothing, and due to the thinness of the foundation, it is possible to have a maximum effective length of tooth and possible to have such teeth straight or of low angularity as may be desired. While such teeth can be made with a bend, the straight tooth at present preferred by most users can be used with full effect. These teeth have sufficient resiliency without being subject to deformation and the clothing is very easily repaired and the teeth replaced if for any reason it should become damaged.

Various modifications may, of course, be made in the construction and arrangement of the strips and teeth. The holes may be variously punched and the teeth either in staple form or in single form variously set in such foundation and attached thereto by soldering, swaging or other means as may be desired.

What we therefore claim and desire to secure by Letters Patent is:—

1. A clothing for cards and the like, comprising a foundation member of thin flexible metal having apertures punched therein, reinforcing metal collars about said apertures and metal points in said collared apertures, said foundation member, said collars and said points all being coated with a sealing material whereby all parts are bound to each other in unitary assembly.

2. A clothing for cards and the like comprising a foundation member of thin flexible metal having apertures punched therein, reinforcing metal collars about said apertures and staple shaped metal points lodged in each pair of said collared apertures, said foundation member, said collars and said points all being coated with a sealing material whereby all parts are bound to each other in unitary assembly.

In testimony whereof we affix our signatures.

EDMOND E. FOURNIER.
